LASTING MACHINE

Jacob C. Jorgensen, Beverly, Mass., assignor to
United Shoe Machinery Corporation, Paterson,
N. J., a corporation of New Jersey

Application April 12, 1937, Serial No. 136,373

48 Claims. (Cl. 12—14)

This invention relates to lasting machines, and more particularly to machines for lasting the toe ends of shoes. An object of the invention is to provide a machine so constructed that in lasting 5 shoes made on ordinary lasts satisfactory results will be obtained in the lasting of each shoe and substantially uniform results in operating on different shoes without the necessity for the operator to exercise any great care or to spend any substantial amount of time in properly presenting 10 each shoe to the machine or in relatively adjusting the shoe and the lasting means. The invention is herein illustrated as embodied in a machine in which the lasting operation is performed by the operator, but in various aspects 15 the invention is also applicable to machines having power-operated lasting means.

The machine herein shown is provided, as common heretofore, with wipers guided for advancing 20 and closing movements in predetermined paths lengthwise and laterally of the shoe and formed to embrace the toe end of the shoe closely at the edge of the shoe bottom, the wipers being movable heightwise of the shoe to perform what 25 is known as the "upwiping" operation before they are further advanced and closed to wipe the margin of the upper inwardly over the shoe bottom. Satisfactory results in the lasting operation require such a relation between the shoe and the 30 wipers that the wipers, when advanced and closed a certain distance, will properly embrace the toe and will thereafter wipe the margin of the upper inwardly over the shoe bottom with adequate pressure all around the toe. To this end, the 35 machine herein shown is so constructed as to determine accurately in certain respects the relation between the shoe and the paths of movement of the wipers before the wipers operate on the shoe, but to permit in one respect a relative 40 movement of the shoe and the wipers into proper relation as an incident to the lasting operation. As illustrated, the position of the shoe lengthwise is determined by an end gage in contact 45 with its toe-end face, and the relation of the bottom of its forepart to the plane of the wipers is determined by a member engaging that portion 50 of the shoe and against which the shoe is clamped by a toe rest. At its heel end, moreover, the shoe is engaged by a heel rest which determines invariably for different shoes, whether 55 rights or lefts, the position of the heel end laterally. The shoe, however, is further so controlled as to permit its toe end to adjust itself laterally to the wipers, thus avoiding the necessity for any exact positioning of the shoe in this respect by

the operator or for the provision of special means for predetermining the position of the toe end laterally. To permit and facilitate such lateral movement of the toe end of the shoe, the shoe support or holder, including the bottom-engaging 5 member and the toe rest, is mounted to swing with the shoe about an axis in the vicinity of its heel end in response to pressure of the wipers on one side or the other of the toe exteriorly of the shoe bottom as the wipers are closed about 10 the toe. The shoe may thus adjust itself readily to the wipers not only prior to the upwiping operation, but during that operation, so that regardless of the shape of the shoe at the sides of the 15 toe the pressures of the wipers on the opposite sides will be substantially equalized. It will be evident that since the toe end of the shoe thus adjusts itself laterally to the wipers, and since the position of its heel end laterally is determined as above described, insurance is afforded 20 that the wipers will properly fit the toe when advanced and closed about the toe, the wipers, of course, being properly designed with reference to a shoe positioned in the above-described relation to their paths of movement. 25

To insure that in the wiping of the margin of the upper inwardly over the insole after the upwiping operation the wipers will close substantially equal distances over the insole, the invention further provides means for preventing in 30 the overwiping operation any such relative movement of the shoe and the wipers in a direction laterally of the shoe as may occur in the upwiping operation. In the construction shown this means comprises a slide connected to the shoe 35 holder to be moved by the latter in directions laterally of the shoe, and a device controlled by the upwiping movement of the wiper support for engaging this slide to lock the shoe holder against further movement when the wipers arrive sub- 40 substantially at the edge of the shoe bottom.

In a further aspect, the invention relates more particularly to the control of members provided for determining the position of the shoe. In the construction shown the toe wipers are moved 45 by the operator to perform the lasting operation, and the heel rest also is moved by the operator into engagement with the shoe, but power-operated means is provided for locking the heel rest in operative position, for operating the toe rest 50 to clamp the shoe, and for moving the toe-end gage out of operative position. The starting of the power-operated means results from depression of a treadle by movement of which the heel rest is first applied to the shoe, and upon a sec- 55

ond depression of this treadle after the lasting operation the power means is again started to cause it to unlock the heel rest and to return the toe rest and the toe-end gage to their initial positions. Various novel features of the invention are to be recognized in this organization.

The above and other features of the invention, including also novel means affording provision for withdrawal from operative position of the positioning member engaging the bottom of the forepart of the shoe, novel means for supporting the shoe and last at the cone of the last, and various novel details of construction and combinations of parts, will now be more particularly described with reference to the accompanying drawings and thereafter pointed out in the claims.

In the drawings,

Fig. 1 is a view in front elevation of a machine in which the invention is embodied, showing the parts as they appear after a shoe has been positioned and clamped ready for the toe-lasting operation, portions of the structure being broken away;

Fig. 2 is a view of the machine in right-hand side elevation, with parts broken away;

Fig. 3 shows in right-hand side elevation, on an enlarged scale, mechanism provided for locking the shoe support or holder against swinging movement after it has assumed a position determined by engagement of the wipers with the shoe;

Fig. 4 shows in front elevation, on an enlarged scale, a device shown also in Fig. 1 for locking the toe rest in operative position;

Fig. 5 is an enlarged plan view of the major portion of the machine, with parts broken away;

Fig. 6 is an enlarged view in front elevation of the heel rest and parts associated therewith;

Fig. 7 is a plan view of the heel rest with parts in section on the line VII—VII of Fig. 6;

Fig. 8 is a perspective view of the upper portion of the machine with the parts as they appear before a shoe is presented.

Fig. 9 shows in right-hand side elevation, with parts broken away, certain operating mechanism shown also, in part, in Fig. 2;

Fig. 10 is a perspective view of a portion of the structure shown in Fig. 3 and of other parts associated therewith; and

Fig. 11 is a sectional view illustrating the relation of the toe of the shoe to the wipers in the upwiping operation.

The machine herein shown is provided with toe-lasting means generally similar to means commonly used heretofore in lasting machines of the bed type and in most respects similar to the disclosure of United States Letters Patent No. 1,018,477, granted on February 27, 1912 upon an application of Matthias Brock. Accordingly such means need be only briefly described, and it will be further understood that the invention is not limited to the use of lasting means of this particular character.

For wiping the upper heightwise of the toe and for thereafter wiping its margin inwardly over the shoe bottom there are provided toe-embracing wipers 2 having wiping edges curved to conform substantially to the contour of the end and sides of the toe adjacent to the edge of the shoe bottom, these wipers being detachably secured to wiper carriers 4 (Fig. 5) mounted on a holder 6. The wiper carriers 4 are provided with cam slots 8 and 10 cooperating with rolls (not shown) on the holder 6 to determine the paths of advancing and closing movements of the wipers lengthwise

and laterally of the shoe. The carriers 4 are connected by links 12 to a crossbar 14 fast on the end of a rod 16 movably mounted in a cylindrical extension 18 of the holder 6 and connected by a link 20 to a wiper-operating hand lever 22. By means of its cylindrical extension 18 the holder 6 is mounted on a support 24 (Fig. 1) which is carried by a slide 26 adjustable horizontally lengthwise of the shoe along a guideway on a plate 28. The slide 26 in the construction herein shown is adjustable in that manner by means of a hand wheel 30 at the front of the machine connected by worm gearing 32 to a shaft 34 rotatable on the plate 28 and threaded in a portion of the slide 26. The wiper holder 6 may be turned about the axis of its cylindrical extension 18 by a hand crank 36, and the support 24 may be swung about a rod 38 extending laterally of the shoe by means of a hand crank 40. The wipers may thus be tipped about axes extending lengthwise and laterally of the shoe to positions such as to produce the best results in wiping the margin of the upper materials inwardly over the shoe bottom; but in view of the character of the means hereinafter described for properly positioning each shoe, any such adjustment will be rarely required.

The plate 28 is part of a slide 42 which is vertically movable in a guideway in the frame of the machine and is connected by a link 44 to a crank arm 46 fast on a rock shaft 48. Also fast on this rock shaft is a double-acting treadle 50 comprising arms 52 and 54 arranged to be acted upon respectively by the forepart and the heel of the operator's left foot. By depression of the arm 52 of the treadle the slide 42 and the parts supported thereon are raised to cause the wipers 2 to wipe the upper heightwise of the toe after they have been advanced and closed about the toe by the hand lever 22, and as the wipers are further advanced and closed to wipe the margin of the upper inwardly over the insole they may be forced downwardly upon the shoe bottom by depression of the arm 54 of the treadle, as in prior machines provided with toe-lasting means of the same general type.

The position of each shoe lengthwise relatively to the paths of movement of the toe wipers is determined invariably for different shoes by a toe-end gage 56 which is part of a forwardly extending arm of a lever 58 mounted for swinging movement about a horizontal rod 60 fast on the frame of the machine and located a substantial distance rearwardly of the shoe, this lever being controlled by mechanism hereinafter described. Initially the gage 56 is positioned somewhat above the plane of the wipers for contact with the toe-end face of the shoe as the operator presents the shoe to the machine. The height at which the shoe is thus presented is determined by a shoe-positioning arm 62 supported as hereinafter described, this arm being provided at one end with three bosses 64 (Fig. 5) arranged to engage the forepart of the insole. The arm 62, therefore, has virtually a three-point bearing on the bottom of the forepart of each shoe and accordingly determines invariably for different shoes of the same style and size the relation of the bottom of the toe end or forepart of each shoe to the plane of the wipers. Insurance is thus afforded that the wipers will operate with uniformly satisfactory results on the different shoes in wiping the margin of the upper inwardly over the insole. It will be understood that by use of the hand crank 40 the wipers may be tipped about the axis of the 75

rod 38, as hereinabove described, to vary as desired the amount of downward pressure which they will apply to the margin of the upper materials at the end of the toe as compared with the pressure applied at the sides of the toe, and that by use of the hand crank 36 the wipers may be tipped laterally to vary relatively the pressures applied at the opposite sides of the toe. Such adjustments may be desirable, for example, when 10 shoes of different styles vary substantially in shape or when there is a substantial difference in the character of the upper materials as between different lots of shoes, but it will be understood that after the wipers have been properly 15 adjusted for shoes of a given style and character, no further adjustment will ordinarily be needed in operating upon such shoes.

After the shoe has been presented with its toe-end face in contact with the gage 56 and the bottom of its forepart in contact with the bosses 64 of the arm 62, it is engaged at the heel end by a heel rest which assists in holding it against heelward movement in the lasting operation and also serves to centralize its heel end laterally. 25 This heel rest comprises a block 66 (Figs. 6 and 7) arranged to press on the extreme end face of the shoe and a pair of arms 68 arranged to engage the corners of the heel end of the shoe in locations near the heel seat. Preferably, as 30 shown, the block 66 carries a cushion 70 of felt or rubber on its shoe-pressing face and is also provided with a strip of leather 72 extending over the cushion. The block 66 is mounted on a pin 74 for limited turning movement about an axis 35 extending laterally of the shoe, this pin being mounted on a slide 76 which is movable in directions lengthwise of the shoe in a block 78. The two arms 68 are mounted to swing toward and from each other about pins 80 in the block 78 40 and are connected by gear teeth 82 with corresponding teeth of the slide 76 so that the arms have equal movements. This slide is controlled by a spring 84 which tends to move it in a direction to swing the arms 68 away from each other, 45 its movement in that direction being limited by a pin 85 thereon in engagement with the block 78 at the end of a slot 86 (Fig. 8) in the block. The block 78 is supported on a bracket 87 and is adjustable along a curved guideway 88 on this 50 bracket, the center of curvature of this guideway being located substantially at the heel-end face of the shoe when the heel rest is in contact with the shoe. The block is held in adjusted position on the bracket by a screw 90 which is 55 threaded in the block and extends through a slot 92 in the bracket, the screw being provided with a knurled head 94 engaging a washer 96 which bears against the bracket and has a tongue extending into the slot 92. The bracket 87 is provided with a stem 98 clamped adjustably in the upper end of an upwardly extending arm 100 of a lever 102 mounted to swing about a rod 104 on the frame of the machine. It will be understood that the bracket 87 may be adjusted upwardly or 60 downwardly relatively to the arm 100 and that the block 78 may be adjusted relatively to the bracket, to position the heel rest in proper relation to shoes of different styles and sizes. The lever 102 is operated by means hereinafter described to carry the heel rest into engagement with the shoe. In this operation the block 66 arrives first in position to press on the shoe, whereupon the arms 68 are swung inwardly into engagement with the corners of the heel end of 65 the shoe by the action of the slide 76 thereon as

the arm 100 continues its movement against the resistance of the spring 84. The arms thus determine invariably for different shoes the position of the heel end of each shoe laterally, whether the shoes be rights or lefts and regardless of the styles or sizes of the shoes; and as the heel end of each shoe is thus positioned, a point on the heel seat midway between the two arms 68 lies in the vertical plane in which the meeting point of the edges of the toe wipers 10 travels lengthwise of the shoe in the operation of the wipers. The heel end is thus centralized laterally relatively to the paths of movement of the wipers. After the heel rest has engaged the shoe its forepart is clamped against the arm 62 15 by a toe rest 106 operated by means hereinafter described and the end gage 56 is withdrawn from operative position to permit the operation of the wipers.

In presenting each shoe the operator will naturally position its forepart so that, as far as he can readily observe, the shoe-engaging end of the arm 62 will be substantially midway between the opposite side edges of the shoe bottom. In order to relieve the operator of the necessity 25 for exercising any particular care in this respect, and in order to insure that notwithstanding such small variations as there may be in the positions of the toe ends of different shoes the toe wipers will nevertheless properly conform to the 30 toe and will bear with substantially equal pressures on the opposite sides of the toe in the upper-wiping operation, the machine is further so constructed that the toe end of each shoe will adjust itself laterally to the wipers in response to pressure of the wipers on one side or the other of the toe. For this purpose the arm 62 and the toe rest 106, which constitute parts of a shoe support or holder, are so mounted as to permit them to swing with the shoe about an axis extending 35 heightwise of the shoe in the vicinity of its heel end. The shoe support or holder includes a substantially vertical bar 108 (Figs. 1 and 2) provided at its upper and lower ends respectively with forwardly extending arms 110 and 112. The 40 upper arm 110 is provided with a stud 114 extending upwardly into an opening in a bracket 116 fast on the frame of the machine and is engaged by a ball bearing 118. In vertical alignment with the stud 114 is a stud 120 which is 45 threaded in the frame of the machine and provides a bearing for the lower arm 112, the lower face of this arm resting on a ball thrust bearing 122. Extending lengthwise of the shoe from the bar 108 and curved laterally of the shoe (Figs. 50 5 and 8) is an arm 124 terminating in a guide 126 for means hereinafter described for supporting the toe rest 106. The shoe-positioning arm 62 is supported on the upper forwardly extending arm 110 of the bar 108 and is pivotally 55 mounted for upward and downward swinging movements on a rod 128 supported in ears on the arm 110. In its operative position the arm 62 is held against upward swinging movement by a latch 130 fast on a rod 132 mounted for turning movement in other ears on the arm 110. A spring 134 mounted in the arm 110 and engaging a tail 136 of the latch 130 holds the latch normally in operative position, as shown in Fig. 1. By depressing an arm 138 fast on the rod 132 the latch 70 136 may be withdrawn from operative position to permit the arm 62 to be swung upwardly away from the shoe while the wipers are over the shoe bottom. This may be done, for example, to provide more room for driving fastenings to fasten 75

the upper in lasted position, if the upper is to be fastened in that manner, or in operating upon a welt shoe to provide more room for applying a wire binder about the toe. At one end the spring 5 134 engages the head of a pin 140 (Fig. 5) mounted for limited movement in the arm 110, one end of this pin bearing against a portion of the arm 62 below the rod 128. Accordingly, the 10 spring-pressed pin 140 tends to swing the arm 62 upwardly, and may do so to some extent when the arm is released by the latch 130, the pin serving in any case to prevent the arm from being swung downwardly by gravity beyond the position determined by the latch.

15 From the foregoing description it will be evident that the shoe support or holder, including the bar 108, the arm 62 and the toe rest 106, may swing with the shoe in one direction or the other about the axis determined by the studs 114 and 120 in response to pressure of the toe wipers on one side or the other of the toe when the wipers are closed about the toe, so that the toe end of the shoe is permitted to adjust itself laterally to the wipers. It will also be evident 20 that while the relation of this axis to the heel end of the shoe will vary somewhat for shoes of different sizes, it will, in any case, be located in the vicinity of the heel end of the shoe, and accordingly the heel rest will not interfere with such 25 small movement as the shoe may receive in adjusting itself to the wipers. The heel end of the shoe being centralized laterally relatively to the paths of movement of the wipers as hereinbefore described, and the toe end thus centralizing itself relatively to the wipers, insurance is afforded 30 that the wipers will properly fit the toe at the edge of the shoe bottom when advanced and closed a definite distance, the wipers, of course, being properly designed with reference to a sole pattern corresponding to the bottom of a shoe 35 thus positioned. It will be understood that different wipers will be required respectively for right shoes and left shoes, as well as for shoes that differ materially in style or size. The shoe first adjusts itself to the wipers when the latter 40 are closed about the toe below the edge of the shoe bottom prior to the upwiping operation, and may further adjust itself during the upwiping operation so that the pressures of the wipers 45 against the upper at the opposite sides of the toe will be substantially equalized. Such further adjustment will occur, for example, if the shoe is shaped as illustrated in Fig. 11, one side of the toe having an outward inclination toward the edge 50 of the shoe bottom and the opposite side an inward inclination.

55 It is desirable to prevent any lateral movement of the toe end of the shoe during the wiping of the margin of the upper inwardly over the insole, so as to insure that the wipers will move inwardly equal distances from the opposite side edges of the shoe bottom. The machine is accordingly provided with means for locking the shoe holder against any further swinging movement when the 60 wipers arrive substantially at the edge of the shoe bottom in the upwiping operation. For this purpose the guide 126, previously referred to as part of the arm 124, has integral therewith short arms 142 and 144 (Figs. 1 and 10) provided with a 65 vertical pin 146 on which is mounted a roll 148. This roll lies in a slot 150 formed in a horizontal slide 152 movable in directions laterally of the shoe in a guideway formed in a block 154 which is fastened to an extension 156 of the plate 28 70 previously referred to as movable upwardly and

downwardly with the toe wipers. Accordingly, any swinging movement of the shoe holder is accompanied by movement of the slide 152 along its guideway in the block 154. Mounted in a recess in the block below the slide 152 are two arms 5 158 (Fig. 3) arranged to swing about pins 160 fast in the block, the upper ends of these arms having eccentric faces 162 arranged to engage the lower face of the slide 152 and to lock the slide frictionally when the arms are swung toward each other. A spring 164 connected to the two arms tends thus to swing them toward each other. Normally, however, they are held far enough apart to permit movement of the slide 152 by a wedge member 166 which engages rolls 10 168 on the arms and is fastened on the frame of the machine. The wedge member is adjustable upwardly or downwardly along a guideway in the frame and is held in adjusted position by a screw 170 threaded in the frame and extending through a slot 172 in the wedge member. The member is so adjusted that as the two arms 158 are moved upwardly with the wipers in the upwiping operation they are permitted to be swung by the spring 164 into positions to lock the slide 152 and 20 the shoe holder when the wipers arrive substantially at the edge of the shoe bottom. Formed on the top of the slide 152 is a lug 174 which is engaged on its opposite sides by two springs 176 mounted in the block 154. These springs insure 25 against any excessive movement of the shoe holder when the machine is idle, and tend to return it to a central position after the lasting of each shoe. It will be understood that these are comparatively light springs, so that they do not oppose 30 any considerable resistance to the swinging movement of the shoe holder in response to pressure of the wipers on one side or the other of the toe.

The heel rest is swung into engagement with the shoe by depression of a treadle 178 fast on a rock shaft 180 at the base of the machine, this shaft having also fast thereon an arm 182 pivotally connected to an upwardly extending rod 184. The pivotal connection between the arm and the 40 rod comprises a pin 186 arranged to enter any one of a plurality of holes 188 (Fig. 9) in the rod to vary the normal position of the heel rest for shoes which differ substantially in size. The rod 184 extends upwardly through a block 190 which 45 is pivotally mounted on the end of a substantially horizontal arm 192 of the previously mentioned lever 102, and between the upper end of this block and a nut 194 on the rod is a spring 196. It will thus be seen that as the treadle 178 is depressed 50 the lever 102 is swung to apply the heel rest to the shoe by downward movement of the rod 184, the spring 196 being yieldable in response to further movement of the treadle when the heel rest is in operative position. A flange 198 on the rod 55 184 serves by engagement with the lower end of the block 190 to determine the normal position of the rod relatively to the arm 192. The heel rest is swung away from the shoe by gravity acting on the arm 100 of the lever 102, and this lever serves to return the treadle 178, the movement of which is limited by engagement of a screw 200 thereon with a shoulder 202 on the frame.

Further movement of the treadle 178 after the 70 heel rest has been applied to the shoe serves to actuate power means through the operation of which the toe rest 106 is forced against the shoe and locked, the heel rest is locked in operative position, and the toe end gage 56 is swung out of 75

operative position. This power means comprises cooperating clutch members 204 and 206 (Fig. 1) having teeth on their opposed faces, the member 204 being part of a continuously driven pulley 208 mounted loosely on a shaft 210. The clutch member 206 is keyed to the shaft 210 to turn therewith and is movable also lengthwise thereof. A plurality of springs 212 tend to force the member 206 into engagement with the member 204, but the member 206 is normally held out of such engagement by a clutch-controlling arm 214 (Fig. 9) in wedging engagement with one side of a lug 216 on the member 206. The arm 214 is fast on a rock shaft 218 and is controlled by a spring 220 which normally holds it in operative position to disconnect the clutch members. Also fast on this rock shaft is an arm 222 engaged by an arm 224 of a bell-crank lever, and the other arm 225 of this bell-crank lever carries a bolt 226 the head of which is arranged to be engaged by a screw 228 carried by the treadle-operated arm 182. The lower end of the screw 228 is spaced initially far enough from the head of the bolt 226 to permit the required movement of the treadle 178 to apply the heel rest to the shoe, and as the treadle is further depressed the clutch-controlling arm 214 is swung downwardly to cause the two clutch members 204 and 206 to engage each other. When the clutch is thus actuated the shaft 210 starts to turn and continues to turn through one revolution, whereupon the arm 214 acts to disconnect the clutch member 206 from the member 204, the treadle having been released by the operator.

The shaft 210 carries a gear wheel 230 in operating engagement with another gear wheel 232 which has twice as many teeth as the gear wheel 230 so that it makes only half a revolution before the shaft 210 comes to a stop. A pin 234 eccentrically mounted on the gear wheel 232 is connected by a link 236 to a lever 238 fast on a rock shaft 240 mounted in bearings in the frame. The lever 238 has a forked end pivotally connected to two blocks 242 (Fig. 1) mounted to slide in horizontal guideways formed in opposite sides of a sleeve 244 movable upwardly or downwardly on a bar 246. Between a shoulder on this sleeve and a collar 248 fast on the bar 246 is a compression spring 250. At its upper end the bar 246 is guided in a bearing in the frame and carries a forked member 252 which supports a roll 254. The member 252 has a depending stem 256 mounted in a bore in the bar 246 and is held from turning by a pin 258 which lies in a slot in the bar. Supported on the roll 254 is the lower end of a toe post 260 slidably movable upwardly and downwardly in the previously mentioned guide 126 of the shoe holder and held from turning by a key 262. The toe post 260 supports on its upper end a holder 264 for the toe rest 106, this holder having a depending stem 266 mounted in a bore in the post and held from turning by a pin 268 lying in a slot in the post. By means of a screw 270 the toe rest may be adjusted in directions lengthwise of the shoe relatively to its holder 264 along a guideway on the holder. It will thus be seen that the toe rest 106 is forced upwardly to clamp the shoe against the arm 62 by upward swinging movement of the lever 238, the spring 250 being compressed more or less in this operation. At its lower end the toe post 260 is provided with a flange 272 (Fig. 8) for engagement with the roll 254 during any swinging movement which the shoe holder receives in the adjustment of the shoe to the wipers.

The lower end portion of the bar 246 (Fig. 9)

is of rectangular shape and is mounted in a guideway in the frame. Above the guideway the bar is provided with a plurality of ratchet teeth 274 arranged to be engaged by a pawl 276 (Figs. 1 and 4) to hold the toe rest 106 positively in shoe-supporting position. The pawl is pivotally mounted on an upwardly extending arm of a lever 278 pivoted at 280 on the frame of the machine, this lever having a downwardly extending arm which carries a roll 282 controlled by a cam block 284 fast on a slide 286 (Fig. 9) which is vertically movable in a bore in the lower end portion of the bar 246, the cam block extending through a slot 288 in this portion of the bar. A pin 290 threaded in the slide 286 and extending through a slot 292 in the lower portion of the bar 246 is connected to a rod 294 extending upwardly through an opening in a lug 296 on the sleeve 244, and between this lug and a washer 298 held by a pin on the upper end of the rod is a spring 300. Accordingly, as the sleeve 244 is moved upwardly along the bar 246 after the toe rest has engaged the shoe the slide 286 is moved upward yielding by the sleeve through the spring 300 and causes the cam block 284 to swing the lever 278 in the direction to carry the pawl 276 into engagement with the ratchet teeth 274. The pawl then holds the toe rest 106 positively in any position to which it is moved in clamping the shoe against the arm 62, since the pressure of the roll 282 on the cam block 284 is not sufficient to cause any downward movement of the cam block against the resistance of the spring 300. In the return of the parts to starting positions the lug 296 engages a shoulder 302 on the rod 294 to impart downward movement to the cam block 284, the pawl 276 then being swung out of engagement with the ratchet teeth by a spring 304 connected to the tail of the pawl.

In order to guard against any downward swinging movement of the heel end of the shoe in response to pressure of the ends of the wipers on the bottom of the shoe in case, for example, the toe rest should be so adjusted as to be located substantially nearer the end of the toe than the ends of the wipers, the shoe support or holder is further provided with means for supporting the shoe and last in a location at the cone of the last. This supporting means comprises a rod 306 adjustably clamped in a holder 308 and having an enlarged head 310 arranged to engage or support the top of the cone of the last in the location indicated in Fig. 1. The holder 308 is adjustable by swinging movement in directions lengthwise of the shoe about the shank of a screw 312 (Fig. 10) whereby the holder is clamped in adjusted position on a vertical slide 314 movable in a guideway formed in a bracket 316 fast on the guide 126. A spring 318 tends to move the slide 314 upwardly and holds it normally in a position determined by engagement of lugs 320 at its lower end with the bracket 316. When the operator presents the shoe to the machine he places the cone of the last against the head of the rod 306 and thereby forces the slide 314 downwardly to the position determined by the last and shoe when the shoe is in proper relation to the arm 62. Thereafter the slide is locked against any further downward movement by a pawl 322 (Fig. 1) pivoted on the bracket 316 and arranged to engage ratchet teeth 70 on the slide. For controlling this pawl there is provided a rod 324 pivotally connected to a lug 326 on the member 252, this rod extending upwardly through an opening formed in a tail 328 of the pawl and carrying a spring 330 mounted be-

tween the tail of the pawl and a collar on the rod. Accordingly, as the member 252 is moved upwardly to force the toe rest against the shoe, the pawl 322 is forced yieldingly against the ratchet teeth of the slide 314 through the spring 330. In the return of the parts to starting positions an enlarged head at the upper end of the rod 324 acts on the tail of the pawl to swing the pawl away from the ratchet teeth.

10 The heel rest is locked in operative position by a pawl 332 (Figs. 1 and 8) in engagement with ratchet teeth formed on a bar 334 which is pivoted at one end to the arm 108 and is slidily supported on the frame of the machine. The 15 pawl 332 is fast on a pin 336 mounted to turn in an upwardly extending bifurcated arm of a lever 338 pivotally mounted between its ends on the frame, the lower arm of this lever engaging a wedge face 340 of a slide 342 vertically movable 20 in a guideway in the frame. At its lower end the slide 342 is pivotally connected to a link 344 on which is slidily mounted a sleeve 346 (Figs. 1 and 2) pivotally supported on the end of an arm 348 fast on the previously mentioned rock shaft 240. 25 Between the sleeve 346 and a collar 350 fast on the link 344 is a compression spring 352. It will thus be seen that when the rock shaft 240 is turned in a clockwise direction (Fig. 2) by the 30 previously described movement of the lever 238 (Fig. 9) the arm 348 acts through the spring 352 to impart upward movement to the slide 342, and the wedge face 340 of this slide acts to swing the lever 338 (Fig. 1) in a counterclockwise direction. Prior to such movement of the lever 338 it is held 35 by a spring 354 in a position in which the pawl 332 is out of engagement with the teeth of the bar 334, the pawl being controlled by a leaf spring 356 which is fast in the pin 336 and lies between two pins 358 on the lever 338. Accordingly, when 40 the lever 338 is swung as above described, the pawl 332 is carried into abutting engagement with one of the ratchet teeth and then serves to lock the heel rest positively in operative position while forcing it still more firmly against the shoe. In 45 the return of the parts to starting positions the sleeve 346 engages a nut 360 on the lower end of the link 344 and imparts downward movement to the slide 342, thus permitting the spring 354 to disconnect the pawl 332 from the bar 334 50 so that the heel rest may return to its idle position.

The lever 58 which carries the toe-end gage 56 is controlled by an arm 362 (Fig. 2) fast on the rock shaft 240. Pivotally connected to this arm 55 is a link 364 which near its upper end is slidily mounted in a sleeve 366 pivoted on the rear end of the lever 58. Between the upper end of this sleeve and a washer 368 held by a pin on the link 364 is a spring 370, and between the lower end of the sleeve and a collar 372 fast on the link is a spring 374. Pivotally mounted on the frame of the machine is a pawl 376 which is swung by a spring 378 into position to enter a notch 380 formed in a lug on the lever 58 to lock the lever 60 with the toe-end gage in operative position when the lever is in position to permit the pawl thus to act. When the rock shaft 240 is turned in a clockwise direction (Fig. 2) as hereinbefore described, the collar 372 engages a tail 382 of the 65 pawl and swings the pawl out of the notch 380, and the link 364 then acts through the spring 370 to swing the lever 58 to the position in which it is shown in Fig. 2, thus withdrawing the gage 56 from operative position. In the return of the 70 parts of the machine to starting positions the

lever 58 is swung reversely through the spring 374 to return the gage to operative position and the pawl 376 is released by the collar 372 to permit the spring 378 to return it into locking position in the notch 380.

In the operation of the machine, briefly summarized, the operator presents a shoe with the bottom of its forepart in contact with the three bosses 64 of the arm 62 and its toe-end face in contact with the end gage 56, placing the 10 top of the cone of the last against the head 310 of the rod 306 and depressing this rod and its supporting slide 314 to the position determined by the shoe and last. He then depresses the treadle 178 to swing the heel rest into engagement with the heel end of the shoe and to cause it to centralize the heel end laterally. Further depression of the treadle serves to actuate the clutch 204, 206 to cause rotation of the shaft 210 and the gear wheel 232. In this operation of 15 the power-driven parts the heel rest is locked in operative position by the pawl 332, the toe rest 106 is forced up to clamp the shoe against the arm 62 and is locked in shoe-supporting position by the pawl 276, the support for the cone of the last is locked in supporting position by the pawl 322, and the toe-end gage 56 is swung upwardly out of operative position. When these 20 operations have taken place the power-driven parts are brought to a stop automatically by disconnection of the cooperating clutch elements when the gear wheel 232 has made a half-revolution, the treadle 178 having been released by the operator. The operator then proceeds to 25 last the toe of the shoe, advancing and closing the wipers about the toe by the hand lever 22 and raising them by the double-acting treadle 59 to wipe the upper upwardly to the edge of the insole. As the wipers are closed about the toe the shoe holder may be swung with the shoe 30 in response to pressure of the wipers on one side or the other of the toe to permit the shoe to adjust itself to the wipers, and during the up-wiping operation the shoe may further adjust 35 itself in this manner so that the pressure of the wipers is substantially equalized at the opposite sides of the toe. When the wipers arrive substantially at the edge of the shoe bottom the shoe holder is locked against any further swinging movement by the action of the arms 158 on 40 the slide 152. After further advancing and closing the wipers to wipe the margin of the upper inwardly over the insole the operator may, if desired, depress the latch 130 to release the arm 62 and may swing this arm upwardly out of the way to provide more room for fastening the upper in lasted position in case fastenings are to be driven for this purpose or, in operating on a welt shoe, to provide more room for applying a 45 wire binder about the toe. If the arm 62 is thus swung upwardly, the wipers will be left in position over the shoe bottom until after the toe rest has been lowered, in order to prevent the toe rest and the shoe from being forced upwardly 50 by the spring 250. After completing the lasting of the toe the operator again depresses the treadle 178 to actuate the clutch, whereupon the power driven parts are returned to their starting positions, the toe-end gage being returned 55 into proper position for use on the next shoe. Before presenting the next shoe the operator swings the arm 62 downwardly again into the position determined by the latch 130.

Having described the invention, what I claim 70

as new and desire to secure by Letters Patent of the United States is:

5 1. In a lasting machine, the combination with toe-lasting means, of shoe-positioning means mounted for swinging movement with a shoe about an axis extending heightwise of the shoe in a location nearer the heel end of the shoe than said toe-lasting means in response to pressure of said lasting means on one side or the other of the toe exteriorly of the shoe bottom to permit the toe of the shoe to adjust itself laterally to the lasting means.

10 2. In a lasting machine, the combination with toe-lasting wipers formed to embrace the toe end of a shoe, of a shoe holder mounted for swinging movement with the shoe about an axis extending heightwise of the shoe in the vicinity of its heel end in response to pressure of the wipers on one side or the other of the toe exteriorly of the shoe bottom to permit the toe of the shoe to adjust itself laterally to the wipers.

15 3. In a lasting machine, the combination with toe-lasting wipers for embracing the toe end of a shoe and for wiping the upper heightwise of the toe, of a shoe holder so mounted as to permit it to swing with the shoe about an axis extending heightwise of the shoe and located heelwardly of its toe portion in response to pressure of the wipers on one side or the other of the toe in the wiping of the upper heightwise of the toe to equalize the pressures of the wipers on the opposite sides of the toe.

20 4. In a lasting machine, the combination with toe-lasting wipers formed to embrace the toe end of a shoe, of a shoe-positioning device arranged to engage the bottom of the forepart of the shoe, and a toe rest for clamping the shoe against said device, said device and the toe rest being mounted for swinging movement with the shoe about an axis extending heightwise of the shoe and located nearer the heel end of the shoe than the toe wipers in response to pressure of the wipers on one side or the other of the toe to permit the toe of the shoe to adjust itself laterally to the wipers in the lasting operation.

25 5. In a lasting machine, the combination with toe-lasting wipers formed to embrace the toe end of a shoe, of a shoe holder comprising members arranged to engage respectively the bottom and the top of the forepart of the shoe to clamp the shoe between them, and a heel rest arranged to engage the heel end of the shoe, said shoe holder being mounted for swinging movement relatively to the heel rest about an axis extending heightwise of the shoe in the vicinity of its heel end in response to pressure of the wipers on one side or the other of the toe to permit the toe of the shoe to adjust itself laterally to the wipers in the lasting operation.

30 6. In a lasting machine, the combination with toe-lasting wipers formed to embrace the toe end of a shoe, of a toe-end gage arranged to determine the position of each shoe lengthwise, a device for determining the position of the heel end of the shoe laterally, and means for clamping the shoe at the forepart in the position thus determined, said clamping means being movable with the shoe about an axis extending heightwise of the shoe and located heelwardly of its toe portion in response to pressure of the wipers on one side or the other of the toe to permit the toe of the shoe to adjust itself laterally to the wipers in the lasting operation.

35 7. In a lasting machine, the combination with toe-embracing wipers, of a shoe-positioning de-

vice for engaging the bottom of the forepart of each shoe to determine invariably for different shoes the relation of the bottom of the forepart to the plane of the wipers, a toe rest for clamping each shoe against said device, and means for invariably centralizing the heel ends of different shoes laterally, said shoe-positioning device and toe rest being movable with each shoe about an axis extending heightwise of the shoe in the vicinity of its heel end in response to pressure of the wipers on one side or the other of the toe to permit the toe of the shoe to adjust itself laterally to the wipers in the lasting operation.

40 8. In a lasting machine, the combination with toe-embracing wipers, of a shoe-positioning device for engaging the bottom of the forepart of each shoe to determine invariably for different shoes the relation of the bottom of the forepart to the plane of the wipers, a toe-end gage arranged to determine the position of each shoe lengthwise, a heel rest for invariably centralizing the heel ends of different shoes laterally, and a toe rest for clamping each shoe against said shoe-positioning device in the position determined by said device and the end gage and heel rest, said shoe-positioning device and toe rest being movable with each shoe about an axis extending heightwise of the shoe and located heelwardly of its toe portion in response to pressure of the wipers on one side or the other of the toe to permit the toe of the shoe to adjust itself laterally to the wipers in the lasting operation.

45 9. In a lasting machine, the combination with toe-embracing wipers, of a shoe-positioning device for engaging the bottom of the forepart of each shoe to determine invariably for different shoes the relation of the bottom of the forepart to the plane of the wipers, a toe-end gage arranged to determine by contact with the toe-end face of each shoe the position of the shoe lengthwise, a heel rest movable into engagement with the heel end of each shoe and provided with means for invariably centralizing the heel ends of different shoes laterally, a toe rest for clamping each shoe against said shoe-positioning device in the position determined by said device and the end gage and heel rest, and means for withdrawing said end gage from operative position after the shoe is thus clamped, said shoe-positioning device and toe rest being movable with each shoe relatively to the heel rest about an axis extending heightwise of the shoe in the vicinity of its heel end in response to pressure of the wipers on one side or the other of the toe to permit the toe of the shoe to adjust itself laterally to the wipers in the lasting operation.

50 10. In a lasting machine, the combination with toe-embracing wipers, of a shoe holder mounted for swinging movement with a shoe and last about an axis extending heightwise of the shoe and located heelwardly of its toe portion in response to pressure of the wipers on one side or the other of the toe to permit the toe of the shoe to adjust itself laterally to the wipers in the lasting operation, said shoe holder comprising members arranged to engage respectively the bottom and the top of the forepart of the shoe to clamp the shoe between them and also comprising a device arranged to assist in supporting the shoe and last at the top of the cone of the last.

55 11. In a lasting machine, the combination with toe-embracing wipers, of a shoe holder mounted for swinging movement with the shoe about an axis extending heightwise of the shoe in the vicinity of its heel end in response to pressure of

- the wipers on one side or the other of the toe to permit the toe of the shoe to adjust itself laterally to the wipers in the lasting operation, said shoe holder comprising a device having an upper arm and a lower arm extending laterally of the shoe to positions at said axis and having also an arm extending lengthwise and laterally of the shoe and provided with a toe rest for supporting the toe end of the shoe.
10. 12. In a lasting machine, the combination with toe-embracing wipers, of a shoe-positioning device for engaging the bottom of the forepart of the shoe, a toe rest for clamping the shoe against said device, said device and the toe rest being movable with the shoe about an axis extending heightwise of the shoe and located heelwardly of its toe portion in response to pressure of the wipers on one side or the other of the toe to permit the toe of the shoe to adjust itself laterally to the wipers in the lasting operation, a member supporting said toe rest, another member movable heightwise of the shoe to operate the toe rest, and a roll on one of said members engaging the other member to facilitate the movement of the toe rest about said axis.
15. 13. In a lasting machine, wipers for embracing the toe of a shoe exteriorly of the shoe bottom and for thereafter wiping the margin of the upper inwardly over the shoe bottom, a support for said wipers, a shoe support, said wiper support and shoe support being relatively movable laterally of the shoe in response to pressure of the wipers on one side or the other of the toe until the shoe and the wipers are in proper relation, and mechanism for thereafter preventing any further such relative movement of the wiper support and the shoe support during the wiping of the margin of the upper inwardly over the shoe bottom.
20. 14. In a lasting machine, toe-embracing wipers for wiping a shoe upper heightwise of the toe and for thereafter wiping its margin inwardly over the shoe bottom, a support for said wipers, a shoe support, said wiper support and shoe support being relatively movable laterally of the shoe in response to pressure of the wipers on one side or the other of the toe in the wiping of the upper heightwise of the toe, and mechanism arranged to become effective when the wipers have substantially completed the wiping of the upper heightwise of the toe to prevent any further such relative movement of the wiper support and the shoe support during the wiping of the margin of the upper inwardly over the shoe bottom.
25. 15. In a lasting machine, toe-embracing wipers movable to wipe a shoe upper heightwise of the toe and thereafter to wipe its margin inwardly over the shoe bottom, a support for said wipers movable with them heightwise of the toe, a shoe support, said wiper support and shoe support being relatively movable laterally of the shoe in response to pressure of the wipers on one side or the other of the toe in the wiping of the upper heightwise of the toe, and locking mechanism arranged to act automatically in response to the movement of the wiper support heightwise of the toe substantially at the end of that movement to prevent any further relative movement of the wiper support and the shoe support laterally of the shoe during the wiping of the margin of the upper inwardly over the shoe bottom.
30. 16. In a lasting machine, the combination with wipers for embracing the toe of a shoe exteriorly of the shoe bottom and for thereafter wiping the margin of the upper inwardly over the shoe bottom, of means for positioning the shoe for lateral movement in response to pressure of the wipers on one side or the other of the toe to permit the shoe to adjust itself to the wipers, and locking mechanism for thereafter preventing lateral displacement of the shoe from the position thus determined during the wiping of the margin of the upper inwardly over the shoe bottom.
35. 17. In a lasting machine, the combination with wipers for embracing the toe of a shoe exteriorly of the shoe bottom and for thereafter wiping the margin of the upper inwardly over the shoe bottom, of shoe-positioning means movable with the shoe in one direction or the other laterally of the shoe in response to pressure of the wipers on one side or the other of the toe to permit the shoe to adjust itself to the wipers, and mechanism for thereafter preventing any further such movement of the shoe-positioning means during the wiping of the margin of the upper inwardly over the shoe bottom.
40. 18. In a lasting machine, the combination with toe-embracing wipers for wiping a shoe upper heightwise of the toe and for thereafter wiping its margin inwardly over the shoe bottom, of a shoe support movable with the shoe in one direction or the other laterally of the shoe in response to pressure of the wipers on one side or the other of the toe in the wiping of the upper heightwise of the toe to permit the shoe to adjust itself to the wipers, and mechanism arranged to act when the wipers have substantially completed the wiping of the upper heightwise of the toe to prevent any further such movement of the shoe support during the wiping of the margin of the upper inwardly over the shoe bottom.
45. 19. In a lasting machine, the combination with toe-embracing wipers for wiping a shoe upper heightwise of the toe and for thereafter wiping its margin inwardly over the shoe bottom, of a shoe support mounted for swinging movement with the shoe about an axis extending heightwise of the shoe in the vicinity of its heel end in response to pressure of the wipers on one side or the other of the toe in the wiping of the upper heightwise of the toe, and mechanism for thereafter locking said shoe support against further swinging movement during the wiping of the margin of the upper inwardly over the shoe bottom.
50. 20. In a lasting machine, the combination with toe-embracing wipers movable to wipe a shoe upper heightwise of the toe and thereafter to wipe its margin inwardly over the shoe bottom, and a wiper support movable heightwise of the toe with the wipers, of a shoe support movable with the shoe in one direction or the other laterally of the shoe in response to pressure of the wipers on one side or the other of the toe in the wiping of the upper heightwise of the toe, and locking mechanism arranged to act automatically in response to the movement of the wiper support heightwise of the toe to prevent any further such movement of the shoe support during the wiping of the margin of the upper inwardly over the shoe bottom.
55. 21. In a lasting machine, the combination with wipers for embracing the toe of a shoe exteriorly of the shoe bottom and for thereafter wiping the margin of the upper inwardly over the shoe bottom, of a shoe support movable with the shoe in one direction or the other laterally of the shoe in response to pressure of the wipers on one side or the other of the toe to permit the shoe to adjust itself to the wipers, a member connected to the shoe support to move therewith,

and means for engaging said member to lock the shoe support against any further such movement during the wiping of the upper over the shoe bottom.

22. In a lasting machine, the combination with wipers for embracing the toe of a shoe exteriorly of the shoe bottom and for thereafter wiping the margin of the upper inwardly over the shoe bottom, of a shoe support mounted to swing with the shoe in one direction or the other laterally of the shoe in response to pressure of the wipers on one side or the other of the toe to permit the shoe to adjust itself to the wipers, a slide connected to the shoe support to be moved thereby, and members arranged to act frictionally on said slide to prevent further movement of the shoe support in either direction laterally of the shoe during the wiping of the upper over the shoe bottom.

23. In a lasting machine, the combination with toe-embracing wipers movable to wipe a shoe upper heightwise of the toe and thereafter to wipe its margin inwardly over the shoe bottom, and a wiper support movable heightwise of the toe with the wipers, of a shoe support movable with the shoe in one direction or the other laterally of the shoe in response to pressure of the wipers on one side or the other of the toe in the wiping of the upper heightwise of the toe, a member movable with the shoe support, and mechanism controlled by the movement of the wiper support heightwise of the toe for engaging said member to lock the shoe support against any further such movement during the wiping of the upper over the shoe bottom.

24. In a lasting machine, the combination with toe-embracing wipers movable to wipe a shoe upper heightwise of the toe and thereafter to wipe its margin inwardly over the shoe bottom, of a shoe support mounted to swing with the shoe in one direction or the other laterally of the shoe in response to pressure of the wipers on one side or the other of the toe in the wiping of the upper heightwise of the toe, a slide connected to the shoe support to be moved thereby, and a device arranged to act on said slide when the wipers have substantially completed the wiping of the upper heightwise of the toe to prevent any further such movement of the shoe support during the wiping of the upper over the shoe bottom.

25. In a lasting machine, the combination with toe-embracing wipers movable to wipe a shoe upper heightwise of the toe and thereafter to wipe its margin inwardly over the shoe bottom, of a shoe support movable with the shoe in one direction or the other laterally of the shoe in response to pressure of the wipers on one side or the other of the toe in the wiping of the upper heightwise of the toe, a slide connected to the shoe support to be moved thereby, a device for engaging said slide to lock the shoe support against movement laterally of the shoe, said slide and device being movable with the wipers heightwise of the shoe, and relatively stationary means arranged to control said device to effect the locking of the shoe support when the wipers have substantially completed the wiping of the upper heightwise of the toe.

26. In a lasting machine, the combination with toe-embracing wipers movable to wipe a shoe upper heightwise of the toe and thereafter to wipe its margin inwardly over the shoe bottom, of a shoe support movable with the shoe in one direction or the other laterally of the shoe in response to pressure of the wipers on one side or the other

of the toe in the wiping of the upper heightwise of the toe, a slide connected to the shoe support to be moved thereby, a pair of arms mounted for swinging movements and having eccentric faces arranged to act frictionally on said slide to lock the shoe support against movement laterally of the shoe, said slide and arms being movable with the wipers heightwise of the shoe, and a device for maintaining said arms in inoperative positions until the wipers have substantially completed the wiping of the upper heightwise of the toe and for then rendering them effective on the slide to lock the shoe support.

27. In a lasting machine, the combination with toe-lasting means movable by the operator to last the toe end of a shoe, of a member for determining the position of the shoe lengthwise by contact with the toe-end face of the shoe, and power-operated means for withdrawing said member from operative position prior to the operation of the toe-lasting means.

28. In a lasting machine, the combination with toe-lasting means movable by the operator to last the toe end of a shoe, of a toe-end gage arranged to serve as an abutment to determine the position of the shoe lengthwise when the shoe is presented to the machine, and power-operated means for clamping the shoe in the position thus determined and for withdrawing said toe-end gage from operative position prior to the operation of the toe-lasting means.

29. In a lasting machine, the combination with toe-lasting means movable by the operator to last the toe end of a shoe, of a shoe-positioning member arranged to engage the bottom of the fore-part of the shoe, a toe rest for clamping the shoe against said member, a toe-end gage for determining the position of the shoe lengthwise by contact with the toe-end face of the shoe, and power-operated means for moving said toe rest into clamping position and for withdrawing said toe-end gage from operative position prior to the operation of the toe-lasting means.

30. In a lasting machine, the combination with toe-lasting means movable by the operator to last the toe end of a shoe, of a toe-end gage arranged to serve as an abutment to determine the position of the shoe lengthwise when the shoe is presented to the machine, a heel rest movable by the operator into engagement with the heel end of the shoe, and power-operated means for locking said heel rest in operative position and for moving said toe-end gage out of operative position prior to the operation of the toe-lasting means.

31. In a lasting machine, the combination with toe-lasting means movable by the operator to last the toe end of a shoe, of a shoe-positioning member arranged to engage the bottom of the fore-part of the shoe, a toe rest for clamping the shoe against said member, a toe-end gage for determining the position of the shoe lengthwise by contact with the toe-end face of the shoe, a heel rest movable by the operator into engagement with the heel end of the shoe, and power-operated means for moving said toe rest into clamping position, for locking the heel rest in operative position and for moving the toe-end gage out of operative position prior to the operation of the toe-lasting means.

32. In a lasting machine, the combination with toe-lasting means, of a toe-end gage arranged to serve as an abutment to determine the position of a shoe lengthwise when the shoe is presented to the machine, a heel rest movable by the oper-

ator into engagement with the heel end of the shoe when thus presented, and power-operated means for clamping the shoe at the forepart and for moving said toe-end gage out of operative position immediately after the movement of the heel rest into engagement with the shoe.

33. In a lasting machine, the combination with toe-lasting means, of a shoe-positioning member arranged to engage the bottom of the forepart 10 of the shoe, a toe rest for clamping the shoe against said member, a toe-end gage for determining the position of the shoe lengthwise by contact with its toe-end face when the shoe is presented to the machine, a heel rest movable by 15 the operator into engagement with the heel end of the shoe when thus presented, and power-operated means for moving said toe rest into clamping position and for withdrawing said toe-end gage from operative position immediately after 20 the movement of the heel rest into engagement with the shoe.

34. In a lasting machine, the combination with toe-lasting means movable by the operator to last the toe end of a shoe, of a shoe-positioning 25 member arranged to engage the bottom of the forepart of the shoe, a toe rest for clamping the shoe against said member, a heel rest movable by the operator into engagement with the heel end of the shoe, and power-operated means for 30 moving said toe rest into clamping position and for locking the heel rest in operative position prior to the operation of the toe-lasting means.

35. In a lasting machine, the combination with toe-lasting means movable to last the toe end 35 of a shoe, of power-operated means for clamping the shoe, a heel rest for engaging the heel end of the shoe, a member movable by the operator to force the heel rest against the shoe, and mechanism controlled by said member for starting 40 said power-operated means.

36. In a lasting machine, the combination with toe-lasting means movable to last the toe end of a shoe, of a shoe-positioning device arranged to engage the bottom of the forepart of the shoe, a 45 toe rest movable to clamp the shoe against said device, power-driven means including a clutch for thus moving the toe rest, a heel rest for engaging the heel end of the shoe, a member movable by the operator to force the heel rest against 50 the shoe, and means for actuating the clutch by the movement of said member.

37. In a lasting machine, the combination with toe-lasting means movable to last the toe end 55 of a shoe, of power-operated means for clamping the shoe at the forepart, a heel rest for engaging the heel end of the shoe, a treadle movable by the operator to force the heel rest against the shoe, and mechanism for starting said power-operated means by further movement of said 60 treadle after the heel rest has engaged the shoe.

38. In a lasting machine, the combination with toe-lasting means movable to last the toe end 65 of a shoe, of a shoe-positioning device arranged to engage the bottom of the forepart of the shoe, a toe rest movable to clamp the shoe against said device, a heel rest for engaging the heel end of the shoe, a member movable by the operator to force the heel rest against the shoe, power-driven means arranged to be started in operation by the 70 movement of said member, and mechanisms for moving the toe rest into clamping position and for locking the heel rest in operative position by the movement of said power-driven means.

39. In a lasting machine, the combination with 75 toe-lasting means movable to last the toe end of

a shoe, of a toe-end gage arranged to serve as an abutment to determine the position of the shoe lengthwise when the shoe is presented to the machine, a heel rest for engaging the heel end of the shoe, a member movable by the operator to force the heel rest against the shoe, and power-operated means controlled by said member for withdrawing said toe-end gage from operative position. 5

40. In a lasting machine, the combination with 10 toe-lasting means, of an arm provided with means for determining the position of a shoe lengthwise relatively to the toe-lasting means by contact with the toe-end face of the shoe, said arm being mounted for swinging movement into 15 and out of operative position about an axis extending lengthwise of the shoe and located at a substantial distance from the shoe widthwise thereof, and means connected to said arm for operating it. 20

41. In a lasting machine, the combination with toe-lasting means, of an arm provided with means for determining the position of a shoe lengthwise relatively to the toe-lasting means by contact with the toe-end face of the shoe, said arm being 25 mounted for swinging movement into and out of operative position about an axis extending lengthwise of the shoe, a link connected to said arm for moving it into and out of operative position, and a latch controlled by said link for locking the arm in operative position and for releasing it to permit its movement out of that position. 30

42. In a lasting machine, the combination with toe-lasting means, of a shoe-positioning device 35 arranged to occupy a position opposite the bottom of the forepart of a shoe and to determine positively the position of the shoe heightwise when the shoe is initially presented to the machine, said device being so mounted as to permit it to 40 be moved away from the shoe prior to the completion of the toe-lasting operation.

43. In a lasting machine, the combination with toe-lasting means, of a shoe-positioning device arranged to occupy a position opposite the bottom 45 of the forepart of a shoe and to determine positively the position of the shoe heightwise when the shoe is initially presented to the machine, said device being mounted for swinging movement heightwise of the shoe to permit it to 50 be moved away from the shoe prior to the completion of the toe-lasting operation, and a member for locking the device in operative position and for releasing it at the will of the operator. 55

44. In a lasting machine, the combination with toe-lasting wipers for wiping the margin of an upper inwardly over the bottom of a shoe, of a device arranged to engage the bottom of the forepart of the shoe to determine positively the position of the shoe heightwise when the shoe is initially 60 presented to the machine, means for clamping the shoe against said device, the device being mounted for swinging movement away from the shoe about an axis extending widthwise of the shoe when the wipers are over the shoe bottom, 65 and a latch for determining positively the operative position of the device and for releasing it to permit its movement away from the shoe. 70

45. In a lasting machine, the combination with toe-lasting means, of means for clamping a shoe 75 and last at the bottom and the top of the forepart for the operation of said toe-lasting means, a device arranged to assist in supporting the shoe and last at the top of the cone of the last, said device being movable to a position determined by 75

the last through pressure of the last thereon, and mechanism for thereafter locking said device against further movement in the same direction.

46. In a lasting machine, the combination with 5 toe-lasting means, of a shoe-positioning member for engaging the bottom of the forepart of a shoe on its last, a toe rest for clamping the shoe against said member, a device arranged to assist in supporting the shoe and last at the top of the cone 10 of the last, said device being movable to a position determined by the last through pressure of the last thereon as the work is presented to the machine, and automatic means for thereafter locking said device against further movement in 15 the same direction.

47. In a lasting machine, the combination with toe-lasting means, of a shoe-positioning member for engaging the bottom of the forepart of a shoe on its last, a toe rest for clamping the shoe 20 against said member, an operating member mov-

able heightwise of the shoe to force the toe rest against the shoe, a device arranged to assist in supporting the shoe and last at the top of the cone of the last, said device being movable to a position determined by the last through pressure of the last thereon as the work is presented to the machine, and mechanism controlled by said operating member for locking said device against further movement in the same direction. 5

48. In a lasting machine, the combination with 10 toe-lasting means, of a support for the forepart of a shoe and last, a member arranged to assist in supporting the shoe and last at the top of the cone of the last, and a slide supporting said member and movable in a direction heightwise of the 15 last to a position determined by the last through pressure of the last on said member, said member being adjustable relatively to the slide by swinging movement lengthwise of the last. 15
